UNITED STATES PATENT OFFICE.

MYER M. SHUSTER, OF PHILADELPHIA, PENNSYLVANIA.

WRENCH.

1,127,100.

Specification of Letters Patent.

Patented Feb. 2, 1915.

Application filed February 16, 1914. Serial No. 818,866.

To all whom it may concern:

Be it known that I, MYER M. SHUSTER, a citizen of the United States, residing in the city and county of Philadelphia, State of Pennsylvania, have invented a new and useful Wrench, of which the following is a specification.

My invention consists of a wrench provided with a movable jaw capable of slipping over and around the corners of the nut and again be held in rigid engagement with a face of said nut, whereby the wrench may be shifted upon the nut without removing it from the latter and have the action of a ratchet wrench.

It further consists of such a wrench in which one jaw can be adjusted in its relation to the other jaw within predetermined limits to admit of the wrench being employed upon nuts of various sizes.

It further consists of other novel features of construction, all as will be hereinafter fully set forth.

The annexed drawings and the following description set forth in detail one mechanical form embodying the invention, such detail construction being but one of various mechanical forms in which the principle of the invention may be used.

In said annexed drawings Figure 1 represents a side view of a wrench having an adjustable span or a so-called monkey-wrench embodying my invention. Fig. 2 represents an edge-view of such wrench. Fig. 3 represents a longitudinal section of such wrench, illustrating the wrench in position with its jaws slipping from one pair of faces of the nut to another. Fig. 4 represents a perspective view of the movable jaw of said wrench. Fig. 5 represents a view, on a smaller scale, of a wrench having a slightly different embodiment of my invention. Fig. 6 represents a view, also on a smaller scale, of a portion of a wrench embodying another embodiment of a part of my invention.

Similar numerals of reference indicate corresponding parts in the figures.

Referring to the drawings, the reference numeral 1 indicates the handle of the wrench, which handle is of a shape to form a convenient grip for the hand. The handle has an enlarged head, 2, from which a stationary jaw, 3, projects, and formed with an opening, 5, through it. A guide-perforation, 6, is formed transversely through the

head and partly intersects the outer wall of the opening to communicate with the latter. A movable and adjustable jaw, 7, corresponding and opposed to the stationary jaw extends laterally from one end of a bar, 8, slidably fitted in the perforation, the outer side of which is open through the outer face of the head, up to the base of the stationary jaw, to admit of sliding motion for the reduced shank, 9, of the movable and adjustable jaw, such opening forming a slot, 10, for said shank, as indicated in dotted lines in Fig. 2 of the drawings. A cogged rack, 11, is formed upon the side of the bar opposite the jaw and is exposed into the outer side of the opening in the head. A worm or screw, 12, is located in said opening and engages the rack, and said worm has at one end an axial pintle, 13, which is journaled in a bore, 14, in one end of the opening, and at the other end an axial stem, 15, of less diameter than the body, 16, of the worm, and engaging in a bore, 17, in the other end of the opening in the head of the wrench, and bearing with its enlarged end, 18, against a spring, 19, in the bore and confined therein by a plug, 20, closing the outer end of the bore. A bolt, 21, is slidably in a longitudinal guide-groove, 22, in the handle and in a guide-opening, 23, forming a continuation of said groove into the opening in the head, and the end of said bolt can engage between the end of the worm and the side of the opening in the head when moved outward, to prevent longitudinal movement of the worm. The bolt has a longitudinal recess, 24, in one side, through which a pin, 25, traversing the groove, projects and retains and limits the longitudinal play of the bolt. The handle has a longitudinal recess, 26, open at both edges of the handle, and one end of the bolt extends into one end of said recess and has an inwardly projecting lug, 27, between which and the end of the recess a spring, 28, is interposed to normally withdraw the bolt from engagement with the end of the worm-body. A latch, 29, having an arm, 30, projecting at about a right angle from its inner end is pivoted at the elbow thus formed in the recess to have the end of said arm bear against the lug of the locking-bolt to have its free portion project through the open side of the recess by the action of the spring normally withdrawing the bolt. An arm,

31, extends inwardly from the free end of the latch and has an arcuate slot, 32, movable upon a pin, 33, traversing the recess.

In practice, the movable jaw is adjusted 5 by means of the worm to have both jaws span the nut, 34, and bear against opposite flat faces of the same, as appears in Fig. 1 of the drawings, and the grasp of the hand upon the handle will force the latch inward 10 to push the locking bolt to engage the body of the worm and keep the same from longitudinal movement. The wrench will thus firmly clasp the nut and can turn the same. When a new grip is to be made upon the 15 nut, the wrench needs not be removed from the nut, but the latch is released to allow the locking bolt to withdraw, when the turning of the wrench upon the nut to get a new grip will allow the movable jaw to slip over 20 the corners of the nut, as illustrated in Fig. 3 of the drawings, as the jaw can slide and move the worm against its spring until the jaws obtain a new grip upon the nut, when the jaw is again locked by grasping the 25 handle and the latch. The action of the wrench will thus be substantially that of a ratchet wrench, and the wrench needs not be removed from the nut each time a new grip is taken. The wrench thus combines the 30 functions of a monkey-wrench and a ratchet wrench.

In the form illustrated in Fig. 5 of the drawings, the adjustable jaw 7 is engaged by the worm 12, but such worm has no longitudinal movement, so that the adjustable jaw is stationary in its adjusted positions. The opposite jaw, 34, has a reduced tongue, 35, which is pivoted in the head of the wrench and a flat spring, 36, is secured 35 upon the edge of the head and bears with its curved free portion against the curved outer edge of the jaw to normally hold the same parallel with the other jaw but allowing said jaw to swing upon its pivot so as 40 to admit of the jaw slipping over the corners of the nut in the same manner as the movable and adjustable jaw of the previously described form of wrench. The sliding bolt 21 is similar to that of said 45 other form and is similarly actuated by the latch 29, and the end of the bolt is forced over the tongue of the movably pivoted jaw to hold the same when turning the nut.

The form illustrated in Fig. 6 has the 50 movably pivoted jaw 34 and the same means for controlling it as the form illustrated in Fig. 5, but the opposite jaw 3 is stationary, like that illustrated in Figs. 1, 2 and 3, so that the wrench is applicable to 55 one size of nuts, only, and not adjustable as the other forms.

When it is desired to hold the movable jaw rigid without the necessity of manually holding the latch down, a pin can be 60 inserted through registering holes, 37, in

the handle and intersecting the recess, which pin engages the end of the arcuate slot in the arm of the latch and retains it in locking position.

Other modes of applying the principle 70 of my invention may be employed for the mode herein explained. Change may therefore be made as regards the mechanism thus disclosed, provided the principles of construction set forth, respectively, in the 75 following claims are employed.

Having thus described my invention what I claim as new and desire to secure by Letters Patent, is:—

1. A wrench, comprising a handle having 80 a head and an outwardly projecting stationary jaw, a jaw transversely movable upon said head opposed to said stationary jaw, means for adjusting the movable jaw in its relation to said stationary jaw, yielding means acting against said adjusting means to force the same and the movable jaw toward the stationary jaw, and a lock 85 adapted to engage said jaw adjusting means and having means for normally maintaining it disengaged.

2. A wrench, comprising a handle having 90 a head and a stationary jaw upon said head, a movable and transversely adjustable jaw opposed to said stationary jaw and having a rack-bar slidably guided in said head, a longitudinally slidable worm in the head and engaging said rack-bar, a spring acting upon said worm to move it in one direction, a bolt longitudinally slid- 100 able in the handle to engage and lock said worm with one end, and a latch in the handle and adapted to slide such bolt.

3. A wrench, comprising a handle having 105 a head formed with a stationary jaw and with an opening through said head having axially alined bores in its sides and with a transverse guide-perforation intersecting the outer side of said opening and the outer face of said head, a movable and 110 adjustable jaw opposed to said stationary jaw and having a bar slidable in the transverse guide-perforation and formed with a rack extending into the aperture of the head, a worm engaging said rack and having an axial pintle and an axial stem rotatable and slidable in the axially alined bores of the aperture, a spring within one of said bores and bearing against the stem 115 of the worm, a locking bolt slidable in the handle and having one end projecting into the aperture of the handle to engage the body of the worm, and means for sliding said bolt.

4. A wrench, comprising a handle having 120 a stationary jaw, an opposed jaw movably supported in the head of said handle, a locking-bolt slidable in said handle and adapted to lock said movable jaw and having at one end a projecting lug, a spring 125

130

bearing against said lug to withdraw said bolt, and a latch pivoted in said handle to partly project through one side thereof and having an arm projecting at an angle from its pivoted end and an arm at its free end formed with an arcuate slot movable upon a pin in the handle.

5. A wrench, comprising a handle having a head, and a stationary jaw upon said head, a movable and adjustable jaw opposed to said stationary jaw and having a rack-bar slidably guided in said head, a longitudinally slidable worm in the head and engaging said rack-bar, a spring acting upon said worm to move it in one direction, a locking-bolt slidable in said handle to have one end engage and lock said worm and having at the other end a projecting lug, a spring bearing against said lug to withdraw said bolt, and a latch pivoted in said handle to partly project through one side thereof and having an

arm projecting at an angle from its pivoted end and an arm at its free end formed with an arcuate slot movable upon a pin in 25 the handle.

6. A wrench comprising a handle having a head and a stationary jaw, a jaw movable in its relation to said jaw, means for adjusting the movable jaw in its relation to 30 said stationary jaw, yielding means acting against said movable jaw-adjusting means to close the jaw, a lock adapted to engage said jaw-adjusting means and for normally withdrawing it from said means, and a 35 latch pivoted in the handle to normally project from the same and engaging the lock to bring it in locking position when pressed into the handle.
